(57) **CLAIM**

The ornamental design for an electronic view finder, as shown and described.

DESCRIPTION

FIG. 1 is a top, front and right side perspective view of an electronic view finder of the present invention;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines in the drawings represent portions of the electronic view finder that form no part of the claimed design. Additionally, the dash-dot-dashed lines in the drawings define the boundaries of the claimed design.
